CLAIM

I claim the ornamental design for a decorative pull, as shown and described.

DESCRIPTION

FIG. 1 is a front view of the decorative pull with a portion of the pull string shown in phantom, the pull string forming no part of the claimed design; and the back view of the decorative pull being a mirror image thereof;

FIG. 3 is a bottom view of the decorative pull;

FIG. 4 is a top view of the decorative pull with a portion of the pull string shown in phantom, the pull string forming no part of the claimed design; and,

FIG. 5 is a perspective view of the decorative pull with an attic door and pull string shown in phantom, the attic door and pull string forming no part of the claimed design.
